UNITED STATES PATENT OFFICE

FRANK H. KNEELAND, OF CHICAGO, ILLINOIS, ASSIGNOR TO SAFETY MINING COMPANY, OF CHICAGO, ILLINOIS, A CORPORATION

RACK FOR GAS DRUMS

Application filed August 15, 1929. Serial No. 386,212.

In the charging of carbon dioxide blasting cartridges it is desirable to employ a plurality of supply drums, all connected to a common header and so arranged that gas may be withdrawn from the drums either selectively or simultaneously. In order that a substantial portion of the contents of the drums may be removed therefrom by gravity, it has been found necessary to invert the drums or in some way support them with the outlets thereof disposed downwardly. For some time it was customary to arrange and support the inverted drums in vertical position in order that the contents might be withdrawn by gravity. With this arrangement considerable difficulty was encountered with freezing valves on the drums, the header and other portions of the piping used to conduct the gas from the drums to the charging apparatus. This difficulty was first attributed to the presence of water in the gas and accordingly a dryer was inserted in the system for the purpose of extracting the water. It was found, however, that this did not eliminate the troublesome freezing. Finally it was discovered that this freezing was due to the partial stoppage of the valves on the drums by scale or other sediment contained in the drums. The result of the clogging of the valves was to permit the gas to expand on leaving the drums, thus producing a refrigerating effect. This refrigerating effect due to the expansion of the gas was responsible for the freezing of the valves on the drum header and other piping. Many attempts were made to overcome this difficulty but without substantial success until it was discovered that by inclining the supply drums at an angle of approximately 45° to the horizontal, the difficulty was overcome. This may be explained by the fact that with a drum in this position there is a pocket or depression below the level of the drum outlet which serves as a settling basin for the scale and other sediment in the drum. In this

way the gas has a free exit through the drum valve and the objectionable refrigerating effect is eliminated. Also, it has been found that with the drums in this position the contents can be removed by gravity almost as rapidly as though the drums were truly vertical.

In view of the foregoing considerations, the object of the present invention is to provide a rack for gas drums wherein the drums may be supported at such an angle as to avoid stoppage of the drum valve.

A further object of the invention is to provide a drum rack of this character capable of supporting a plurality of drums and in which the drums may be rapidly inserted and removed, and when inserted be held in definite spaced relation.

Other objects relate to details of construction which will be hereinafter pointed out.

In the drawing:

Figure 1 is a front elevation of the improved drum rack and

Figure 2 is a vertical section along the line 2-2 of Figure 1.

The framework of the improved drum rack consists of connected front and rear frame units, the latter including vertical end portions 1 and 2 and transverse tie portions 7 and 8. The bar 7 connects the upper ends of the bars 1 and 2 while the bar 8 extends transversely between and connects bars 1 and 2 at points slightly above their mid-portions. Vertical division bars 10 connect the transverse bars 7 and 8. The front frame unit consists of uprights 3 and 4 and the transverse connecting bar 9. This front unit is connected to the rear unit by means of inclined tie bars 5 and 6 at opposite ends of the rack. These inclined tie bars extend from the upper ends of the bars 3 and 4 to the transverse bar 8 of the rear frame unit. The angle bars 12 connect the lower ends of the uprights 1, 2, 3 and 4 and provide means

for securing the rack to a floor or other support.

It will be noted that the transverse tie bar 9 is of right angular cross section and is so positioned that one of its flanges is supported by the surfaces of the inclined bars 5 and 6. In this way the transverse bar 9 provides a channel extending transversely of the drum rack. The other flange of the bar 9 is provided with spaced recesses 11 of such contour as to receive and support the neck portions of gas drums. These recesses are arranged in alignment with the spaces formed by the division bars 10. The purpose of this arrangement will be apparent from an inspection of Figure 2 wherein a gas drum is shown in dotted outline in position on the drum rack.

The transverse tie bar 7 of the rear frame unit is provided with two or more brackets 13 which are designed to receive a header to which the outlets of the various drums may be connected.

Referring to Figure 2 of the drawing it will be observed that the position in which a drum is supported by the improved rack is such as to provide a settling basin adjacent the discharge end of the drum, but out of the path of the gas which flows through the outlet valve. Any scale or other sediment which may be present in the drum will settle by gravity into this settling basin and thus permit unobstructed flow of gas from the drum. It will also be observed that the improved drum rack structure is such as to greatly simplify the interchange of exhausted and refilled gas drums. The improved rack is preferably constructed entirely of angle irons, either riveted or welded together and is therefore of comparatively inexpensive structure, although quite sturdy and capable of long service.

Claims:

1. A rack for gas drums comprising a rear frame unit consisting of spaced upright bars, a transverse tie bar connecting the upper ends of said upright bars, a second transverse tie bar connecting said upright bars below the first said tie bar and substantially above the mid-points of said upright bars, a front frame unit spaced from the rear frame unit and consisting of spaced upright bars of substantially less than one-half the height of the rear frame unit, a transverse tie bar connecting the upper ends of the last said upright bars, inclined end tie bars connecting the upper ends of the last said upright bars with the respective upright bars of the rear frame unit at points above the mid-portions of the latter, the last said transverse tie bar being of right angular cross section and having one of its walls engaging and supported by said inclined tie bars, the other wall being formed with a recess adapted to receive the neck portion of a drum.

2. A rack for gas drums comprising a frame having a transverse rear support and a transverse front support, said supports being at relatively different heights, whereby to position a drum at an angle to the horizontal, said front support being the lower of the two and consisting of a bar of angular cross section having one wall thereof recessed to receive the neck portion of a drum.

Signed at Chicago, Illinois, this 12th day 75 of August, 1929.
